REFRIGERATING APPARATUS

Alfred D. Karr, Newark, N. J., assignor to Ingersoll-Rand Company, Jersey City, N. J., a corporation of New Jersey

Application June 11, 1937, Serial No. 147,618

9 Claims. (Cl. 62—152)

This invention relates to refrigerating apparatus for cooling liquid by subjecting it to reduced pressure, and more particularly to refrigerating apparatus of the type in which a liquid undergoes a series of vaporizing actions at progressively lower pressures to be progressively cooled.

An object of the invention is to assure simplicity and flexibility of operation in apparatus of this type.

Another object of the invention is to avoid complex valving arrangements for controlling the amount of refrigeration produced.

Other objects will be in part obvious and in part pointed out hereinafter.

In the drawing, in which like numerals denote like parts,

Figure 1 is a vertical elevation, partly in section, of refrigerating apparatus constructed in accordance with the practice of the invention.

Figure 2 is a sectional view through Figure 1 on the line 2—2, and

Figure 3 is a sectional view through Figure 1 on the line 3—3.

Referring more particularly to the drawing, the invention is shown embodied in water vapor refrigerating apparatus comprising an evaporator vessel 20 to which suitable evacuators, shown as steam jet boosters 21 and 22, are connected to produce low pressures in the vessel under the action of which water is cooled by partial vaporization.

The evaporator vessel 20 is shown divided into upper and lower compartments by a horizontal partition 23 and is provided with an inlet 24 for water to the upper compartment. An outlet port 25 in the partition 23 leads from the upper compartment into the lower compartment and an outlet 26 serves to drain the water from the bottom of the vessel.

The evacuators 21 are connected to draw vapor from the upper compartment and serve to produce low pressure in the compartment under the action of which a certain degree of cooling is effected in the water in the compartment. The evacuators 22 are connected to draw vapor from the lower compartment and serve to produce lower pressure in this compartment than the pressure produced in the upper compartment.

The cooled water delivered from the upper compartment into the lower compartment is subjected to the lower pressure and is cooled further. The water may then be drained from the lower compartment through a pipe 27 to be impelled to a place of use (not shown) where its

refrigerating effect may be utilized, and the used water may return to the evaporator through a pipe 28 which is connected to the inlet 24 in the upper compartment.

The evacuators 21 and 22 discharge to a condenser 29 of suitable form in which the vapors from the evaporator compartments and the steam from the ejectors is condensed. A suitable vacuum pump (not shown) will be connected to the condenser by a pipe 30 and will serve to remove uncondensable gases from the condenser and to maintain vacuum throughout the system.

The parts so far described are of conventional types in which, as heretofore used, the liquid to be cooled flows continuously through all of the compartments in the evaporator irrespective of the refrigerating load on the system. In prior structures involving these parts it has also been the practice to employ complex valving arrangements in the ejector casings or to employ condenser means having a separate condensing chamber for each ejector to prevent backing up of vapor from the condenser into evaporator compartments which have been rendered inactive to reduce the refrigerating capacity of the evaporator. The present invention avoids such complex structures and the disadvantages attendant therewith, and provides an evaporator having groups of chambers in which liquid to be cooled passes successively from the chambers of one group to the chambers of another group. Any of the chambers may be rendered inactive for refrigerating purposes without destroying the communication between the chamber and the condenser and in each of such inactive chambers refrigerant will automatically cease flowing. The construction in each chamber is such that the only operation necessary to reduce the capacity of the evaporator is the shutting-off of an ejector for a chamber.

In the illustrated form of the invention, the upper compartment of the evaporator vessel contains one group of chambers and the lower compartment contains another group of chambers. Two horizontally disposed chambers 31 and 32 are shown in the upper compartment separated by a vertical transverse partition 33 central in the vessel 20 and depending from the top thereof to a point somewhat above the partition 23.

A trough centrally positioned in the upper compartment and closed at its ends by the side walls of the vessel 20, has side walls or weirs 34 on opposite sides of and spaced from the partition 33 and has a bottom 35 at an elevation intermediate the bottom of the partition 33 and the

partition 23. The trough cooperates with the partition 33 to define inlet wells 36, one in each of the chambers 31 and 32, and the inlet 24 opens into the bottom of the trough below the partition 5 33 to admit liquid to the wells. The weirs 36 terminate short of the top of the vessel 20 to deliver liquid to the chambers, and, if desired, each weir may be provided with a series of ports 37 near its top. Liquid in the wells serves to seal 10 the chambers one from the other.

The chambers 31 and 32 communicate at the bottom beneath the bottom 35 of the trough, and cooled liquid collecting in the chambers serves as a seal between the bottoms of the chambers. 15 The outlet port 25 in the partition 23 serves as a common outlet for liquid from all the chambers of the first group and to deliver such liquid to the chambers of a second group. Each of the chambers 31 and 32 may also be provided with a baffle 20 38 near its bottom for restricting the flow of liquid therefrom.

The outlet port 25 is preferably central in the partition 23 and a conduit 43 connected to the port depends from the partition within the lower 25 compartment of the vessel. Vertical partitions 41 and 42 depending from the partition 23 and connected to the conduit 43 on opposite sides thereof, preferably lie in the same plane and extend to the side walls of the vessel 20 to divide the lower compartment into horizontally disposed chambers 39 and 40.

The conduit 43 and partitions 41 and 42 terminate short of the bottom of the lower compartment, and a trough centrally positioned in the 35 lower compartment and closed at its ends by the side walls of the vessel 20, has side walls or weirs 45 on opposite sides of and spaced from the partitions 41 and 42 and has a bottom 46 below the bottoms of the partitions 41 and 42 and the conduit 43 and above the bottom of the lower compartment. The trough cooperates with the partitions 41 and 42 to define inlet wells 44, one in each of the chambers 39 and 40, and the conduit 43 opens into the bottom of the trough to admit liquid to the wells 44. The weirs 45 terminate short of the partition 23 to deliver liquid to the chambers 39 and 40, and, if desired, may be provided with ports 47 near their tops. Liquid in the wells 44 serves to seal chambers 39 and 40 from 50 each other.

The chambers 39 and 40 communicate at the bottom beneath the bottom 46 of the trough, and cooled liquid collecting in the chambers serves as a seal between the bottoms of these chambers. The outlet 26 from the vessel 20 is preferably central in the bottom of the vessel and serves as a common outlet for liquid from the chambers 39 and 40. The chambers 39 and 40 may also be provided with baffles 48, similar to the baffles 38, 60 which serve to restrict the flow of liquid from the chambers 39 and 40 to the outlet 26.

Suitable means are provided for controlling the amount of liquid delivered to the evaporator vessel and, in the present instance, comprises a 65 pressure actuated valve 49 in the inlet pipe 28. The valve is preferably connected to be actuated by liquid discharged by a pump (not shown) interposed in the refrigerant discharge line 27. To this end a pipe 50 having a branch 51 leads from the discharge of the pump to a diaphragm chamber 52 closed by a diaphragm 53 connected to actuate the valve 49. The pipe 50 opens into a float container 54 and is provided with a valve 55 connected to be actuated by a float 56 within the 75 container.

The container 54 is connected at the bottom by a conduit 57 to the bottom of the lower compartment in the evaporator vessel 20 to admit liquid from the chambers 39 and 40 to the container. A pipe 58 connects the upper part of the container to the interior of the condenser 29 and serves to subject the liquid in the container to condenser pressure. The float will be actuated in accordance with the difference between the pressures in the chamber 39 and in the condenser and 10 in accordance with the liquid level in the container 54, and will serve to control the pressure of the liquid delivered to the diaphragm chamber 52. The valve 49 will be closed when the liquid level rises or the pressure differential 15 decreases and will be opened when the opposite conditions occur.

Each of the chambers 31, 32, 39 and 40 is provided with an outlet 59 near the top thereof and leading into the casing of one of the ejectors 21 20 or 22. Each of these casings opens into the condenser 29 and encloses one or more nozzles 60 to which steam is supplied through a pipe 61 having a valve 62 interposed therein.

The condenser 29, which may be of any desired 25 construction, preferably provides a single condensing chamber 63 into which all of the ejector casings open. In the illustrated form of the invention the condenser is of a barometric type to which water is admitted through a pipe 64 to come 30 into immediate contact with the vapor in the condenser.

The condenser is shown positioned above the evaporator vessel in coaxial alignment therewith and is supported by a member 65 mounted on top 35 of the vessel 20. The member 65 is hollow at its upper end to connect to an outlet 66 in the bottom of the condenser and to connect to a tail pipe 67 for discharging condensate and condensing water from the condenser. 40

The casings of the ejectors 21 are considerably shorter than the casings of the ejectors 22 and all enter the condenser at substantially the same elevation. The ejectors 21 and 22 are preferably alternately and equidistantly spaced around the 45 peripheries of the evaporator and condenser vessels, as shown in Figure 2, in order to uniformly distribute the weight of these members around the vertical axis of the vessels.

It will be understood that more than two groups 50 of chambers and more than two chambers in each group may be provided, if desired, but in any event, each chamber will be provided with a separate evacuator member and a separate inlet well and the chambers of each group will have a common 55 inlet and a common outlet.

The operation of the apparatus is as follows: Under rated refrigerating load all of the ejectors 21 and 22 and chambers 31, 32, 39 and 40 will be in operation. Liquid will be substantially equally 60 divided between the chambers 31 and 32 of the first group and will be subjected to vacua of substantially equal degree in the chambers as maintained by the ejectors 21. The liquid cooled in these chambers will then flow into the chambers 39 and 40 of the second group and will be substantially equally distributed thereto to be subjected to vacua of somewhat higher equal degree than the vacuum in the chambers 31 and 32, and further cooling of the liquid will occur. The 70 vapor from all of the chambers will be discharged into the common condensing space 63.

Should the refrigerating load drop, one or more of the ejector members and evaporator chambers may be shut down by closing a corre- 75

sponding number of valves 62. No particular order of shutting down the ejectors and chambers need be followed for a shutting down of any one of the ejectors will effect a reduction in the 5 refrigerating capacity of the evaporator. It is preferable, however, to first shut off the ejectors 22 for these ejectors must work against the greatest pressure differential.

The number of ejectors in operation may be 10 varied as desired, but so long as any liquid continues to circulate in the system at least one of the ejectors for each group of chambers must be maintained in operation. The reason for this will be apparent when it is considered that in 15 order for liquid to circulate in the system, it must pass through at least one of the chambers in each group of chambers, and if all of the ejectors for any one group of chambers were inactive, the liquid flowing therethrough would come into immediate contact with vapor backing up through 20 the inactive ejector casings into these chambers and be heated by condensing such vapor.

In the illustration, the chamber 32 of the upper or first group and the chamber 40 of the lower or second group and the corresponding ejectors 21 and 22 are shown as inactive. Condenser pressure is now admitted to these chambers and acts upon the liquid in the inlet wells 36 and 44 thereof to depress such liquid below the tops of 30 the weirs 34 and 45, respectively, of these wells and prevent the admission of liquid to the chambers 32 and 40. The liquid is, however, not depressed below the bottoms of the partitions 33 and 41 and 42, and liquid seals between the 35 chambers are maintained in the inlet wells. The liquid in the chambers 32 and 40 is also depressed somewhat below the level of the liquid in the chambers 31 and 39, respectively, but is not depressed below the bottoms of the troughs 40 in the chambers. Thus, the liquid seals between the bottoms of the chambers 31 and 32, and 39 and 40, respectively, are maintained. The liquid in the inactive chambers remains in a quiet state 45 and absorbs relatively little heat from the fluid backing up from the condenser into these chambers.

It will be apparent, therefore, that by arranging the chambers in groups in which liquid refrigerant passes progressively from one group to another, the liquid may be subjected to a series of vaporizing actions under progressively higher vacuum and be progressively cooled. By the provision of an inlet well in each chamber, the liquid seals between the chambers and the common outlet 50 from one group of chambers into another group of chambers, any of the chambers may be rendered inactive, without requirement as to order, by the sole operation of shutting down the ejectors for such chambers. The admission of 55 liquid to these inactive chambers will then be stopped and isolation of such inactive chambers from the condenser is not required.

I claim:

1. Refrigerating apparatus comprising an 60 evaporator vessel, partition means in the vessel defining upper and lower compartments in the vessel, transverse partitions in each of the compartments to define chambers in the compartments, a common liquid inlet means to the chambers of the upper compartment, a common liquid outlet means for the chambers of the upper compartment to deliver liquid to the chambers of the lower compartment, and evacuator members connected to the chambers of the evaporator 65 vessel.

2. Refrigerating apparatus comprising an evaporator vessel, partition means in the vessel defining upper and lower compartments in the vessel, transverse partitions in each compartment to define chambers in the compartments, 5 partitions cooperating with the transverse partitions to define inlet wells for liquid one in each chamber, a common liquid inlet for the wells in the chambers of the upper compartment, a common liquid outlet for the latter chambers to deliver liquid therefrom to the wells in the chambers of the lower compartment, and evacuator members connected to the chambers of the vessel. 10

3. Refrigerating apparatus comprising an evaporator vessel, a horizontal partition defining upper and lower compartments in the vessel, transverse vertical partition means in each of the compartments depending from the tops thereof but terminating short of the bottoms of the compartments to define chambers in each compartment, means cooperating with the vertical partition means to define inlet wells one in each chamber, a single liquid inlet common to the wells in the chambers of the upper compartment, 25 a single liquid outlet common to the latter chambers and forming an inlet common to the wells in the chambers of the lower compartment, and evacuator members connected to the chambers of the vessel. 30

4. In refrigerating apparatus, evaporator means, means in the evaporator means defining upper and lower compartments, means in the compartments to define chambers therein, a single liquid inlet for all the chambers of the upper compartment, a single liquid outlet conduit for all the chambers of the upper compartment to discharge liquid therefrom to the chambers of the lower compartment, means to reduce the pressure in the chambers of the upper compartment, and means to reduce the pressure in the chambers of the lower compartment to a pressure less than the pressure in the chambers of the upper compartment. 40

5. In refrigerating apparatus, evaporator means, means in the evaporator means defining upper and lower compartments, means in the compartments to define chambers in the compartments, a common liquid inlet means for the chambers of the upper compartments, a common outlet means to discharge the liquid from the chambers of the upper compartment to the chambers of the lower compartment and providing a liquid seal between the upper compartment chambers and the lower compartment chambers, 50 means to reduce the pressure in the upper compartment chambers, and means to reduce the pressure in the lower compartment chambers to a pressure below the pressure in the upper compartment chambers. 55

6. In refrigerating apparatus, evaporator means, means in the evaporator means defining upper and lower compartments, means in the compartments to define chambers in the upper compartment and chambers in the lower compartment, a common liquid inlet for the upper compartment chambers, a common outlet for liquid from the upper compartment chambers, a common inlet for liquid to the lower compartment chambers, said outlet delivering into the 70 last said inlet, means to reduce the pressure in the upper compartment chambers, and means to reduce the pressure in the lower compartment chambers below the pressure in the upper compartment chambers. 75

7. In refrigerating apparatus, evaporator means, means in the evaporator means defining upper and lower compartments, means in the compartments to define chambers in the upper compartment and chambers in the lower compartment, an inlet common to the upper compartment chamber, a common liquid outlet for the upper compartment chambers to deliver the liquid into the lower compartment chambers, a vapor evacuator to reduce the pressure in each chamber, and means to vary the number of evacuators in action thereby to vary the number of chambers in action.

8. In refrigerating apparatus, evaporator means, means in the evaporator means defining upper and lower compartments, means in the compartments to define chambers in the upper compartment and chambers in the lower compartment, a common liquid inlet means for the upper compartment chambers, a common liquid outlet means for the upper compartment chamber, a common liquid inlet means for the lower compartment chamber, said outlet means delivering liquid to the last said inlet means, a vapor evacuator for each chamber, means to

render each evacuator inactive, and means associated with the evacuators to increase the pressure in a chamber when the evacuator therefore is inactive, the increased pressure acting on the liquid on the inlet means to prevent admission of liquid in the inactive chamber.

9. In refrigerating apparatus, an evaporator, means in the evaporator means defining upper and lower compartments, means in the compartments to define chambers in the upper compartment and chambers in the lower compartment, a common inlet means and an outlet means for liquid for the chambers of each group, means connecting the outlet means of one group of chambers to the inlet means of another group of chambers to connect the groups of chambers in series, said inlet means providing liquid seals between the chambers of a group and said outlet means providing liquid seals between the chambers of a group and between the chambers of one group of chambers of a succeeding group, and vapor evacuating means connected to the chambers.

ALFRED D. KARR. 21
